(57) CLAIM

The ornamental design for an animal collar component, as shown and described.

DESCRIPTION

FIG. 1 is a top-front perspective view of an animal collar component showing my new design.

FIG. 2 is a bottom-rear perspective view thereof.

FIG. 3 is a left side view thereof.

FIG. 4 is a top view thereof.

FIG. 5 is a right side view thereof.

FIG. 6 is a bottom view thereof.

FIG. 7 is a front view thereof; and,

FIG. 8 is a rear view thereof.

The broken lines showing portions of the animal collar component are included for the purpose of illustrating portions of the article and forms no part of the claimed design.

1 Claim, 7 Drawing Sheets
